W. H. HOLCOMB,
TENNIS COURT TAPE STAPLING DEVICE,
APPLICATION FILED DEC. 21, 1914.

1,199,791.

Patented Oct. 3, 1916.

UNITED STATES PATENT OFFICE.

WILLIAM H. HOLCOMB, OF CHICAGO, ILLINOIS, ASSIGNOR TO J. HUNTER SMITH, OF CHICAGO, ILLINOIS.

TENNIS-COURT-TAPE-STAPLING DEVICE.

1,199,791.

Specification of Letters Patent.

Patented Oct. 3, 1916.

Application filed December 21, 1914. Serial No. 878,460.

To all whom it may concern:

Be it known that I, WILLIAM H. HOLCOMB, a citizen of the United States of America, and a resident of Chicago, county 5 of Cook, and State of Illinois, have invented certain new and useful Improvements in Tennis-Court-Tape-Stapling Devices, of which the following is a specification.

In laying out tennis courts heavy canvas 10 tape is often used to define the lines of the court. These tapes are usually secured to the ground by spikes passing through eyelets at the ends of the tape and by staples driven into the ground at intervals along 15 the length of such tapes.

The main objects of this invention are to provide an improved device for driving and pulling the staples used for holding tennis-court tapes in place; to provide a device of 20 this kind having improved means for supporting the staples and guiding them while they are being driven into the ground; to provide an improved rack arranged to support said staples in position to be conveniently transferred to said supporting means, and to support said staples compactly in 25 position for storage; and to provide improved means adapted to cooperate with the said supporting means for forcing the 30 staples into the ground and having improved means for use in pulling said staples and spikes from the ground.

An illustrative embodiment of this invention is shown in the accompanying drawings, in which:

Figure 1 is a perspective view of the device showing the manner in which it is operated for driving the staples. Fig. 2 is a perspective view showing the manner in which 35 one of the parts of the device is used for pulling the staples. Fig. 3 is a side view of the lower end of this part. Fig. 4 is a perspective view of the rack and chute arranged in the tray in which it is supported 40 when stored away, a part of the tray being broken away and a small number only of the staples being shown on the rack, for the sake of clearness.

In the construction shown, the device comprises three members designated 1, 5 and 20 in the drawings. The member 1, which may be conveniently formed of sheet metal, has the ends thereof bent down so that it may serve as a rack for holding the staples 45 4 both during the operation of driving

staples and when laid on a horizontal surface. One end, part 2, is bent at an angle of about 45° and its edges are bent over to provide opposed guideways 3 and form a chute along which staples 4 slide when they are driven into the ground. The lower edge 60 of the chute has a recess 6 formed therein, the length of which is substantially equal to the width of the tape 7 over which the staples 4 are to be secured. Thus, when the 65 chute is set with the recess 6 straddling the tape the staples 4 are guided so as to enter the ground without danger of injuring the tape.

The rack member 1 is made rigid by having its edges bent to form flanges 8 extending from the chute 2 to the hook-shaped end 9. The width of the rack is equal to the distance between the tines of the staples 4, and shoulders 10 are provided to support the 70 staples as shown. The rack thus serves as a magazine for the staples 4 which, when the rack rests on the part 2 and hook 9, are supported compactly in position for storage, and when the device is held in position for 75 driving staples the staples are held in convenient position to be picked up singly by the operator.

The tool member 5 is provided with a head which is formed of two plates 11 and 12 riveted together, the plate 12 being bent around the end of the plate 11 to provide a claw 13, and the plate 11 being extended beyond the sides of the plate 12 to provide 80 guide flanges 14 adapted to be slid in the guideways 3. The lower end of the member 5 forms a shoulder 15 which may to advantage be flat or slightly concave to insure 85 proper engagement with the staples 4. A shank 16 is secured to the plate 12 and has a handle 17 by which the tool is gripped. The claw 13 is gradually tapered to a sharp edge 18, so that it may be readily inserted under the staple as shown in Fig. 2, and is also 90 bifurcated at 19 so that it may be used for pulling the spikes used in securing the ends 95 of the tapes.

The device is operated in the following manner: With the staples 4 on the rack 1, as shown in Fig. 1, the part 2 is held so that the recess 6 straddles the tape. The lowermost staple 4 is then removed from the rack and transferred to the chute and the member 5 inserted into the chute and 100 pressure applied thereto so that the staple 110

is forced down into the ground to confine the tape 7. The member 5 is then withdrawn and the chute set in the next place at which a staple is to be located, and the 5 operation repeated. When it is desired to take up the tapes, the claw on the member 5 is used for pulling the staples, as shown in Fig. 2. The claw is also used for pulling the spikes that are usually driven through 10 eyelets at the ends of the tape. When the device is to be stored away it is set in the tray or housing 20, as shown in Fig. 4. The staples are thus confined in an orderly manner on the rack.

15 Although but one specific embodiment of this invention has been herein shown and described, it will be understood that numerous details of the construction shown may be altered or omitted without departing 20 from the spirit of this invention as defined by the following claims.

I claim:

1. In a device of the class described, the 25 combination of a chute for guiding staples and having an operating handle, and a member having a part slidably fitting within said chute for driving staples guided thereby, said member being also provided with an operating handle and having a claw on said 30 part, said chute being open at one side to permit the passage of said claw.

2. In a device of the class described, the 35 combination of a channel-shaped open-sided chute for guiding staples and having a shank at one side provided with a handle and arranged to serve as a magazine for staples, and a member comprising a shank having an operating handle at one end and a staple driving head at its opposite end, said head 40 being shaped to slidably fit said chute, and a claw carried by said head and positioned to correspond with the open side of said chute when said head is guided thereby.

3. In a device of the class described, the 45 combination of a chute for guiding staples and having an operating handle, and a member having a part slidably fitting within

said chute for driving staples guided thereby, said member being also provided with an operating handle, said chute being provided 50 with guide means at its lower end for centering the same with respect to a tape which is being stapled.

4. In a device of the class described, the combination of a chute for guiding staples 55 and having an operating handle, and a member having a part slidably fitting within said chute for driving staples guided thereby, said member being also provided with an operating handle, the end of said chute 60 being recessed so as to straddle a tape which is to be stapled and thereby predetermine the position of the staple with respect to the tape.

5. In a device of the class described, the 65 combination of a chute for guiding staples and having an operating handle, and a member comprising a handle and a plate carried by said handle and slidably fitting into said 70 chute, the lower end of said plate being bent transversely to form a shoulder for engaging the staples and to form a claw for pulling the staples.

6. In a device of the class described, the 75 combination of a member having the ends 80 thereof bent to support the intermediate part of said member in a raised horizontal position, the edges of one of said ends being bent to form guideways, said intermediate part being shaped to support staples thereon 85 for storage when said member rests on said ends and to support the staples in position to be readily transferred to said guideways when said member is held in an operating position, and a second member slidably fitting 90 said guideways for driving the staples guided thereby.

Signed at Chicago this 18th day of December, 1914.

WM. H. HOLCOMB.
